UNITED STATES PATENT OFFICE.

ALBERT E. WEAVER, OF INDIANAPOLIS, INDIANA, ASSIGNOR, BY MESNE ASSIGNMENTS, TO IRA T. SWARTZ, TRUSTEE, OF INDIANAPOLIS, INDIANA.

CARBURETOR.

Application filed September 3, 1921. Serial No. 498,335.

This invention relates to carburetors, and one feature of the invention is the provision of means for introducing air into the fuel chamber of the carburetor at a point below the float for aerating the fuel and agitating the float and imparting thereto a more sensitive action, and providing a positive action for the float in the event of the increase of vacuum above the float.

10 A further feature of the invention is the provision of a chamber having an automatic valve therein which automatically closes on the stopping of the engine, and prevents backfire through the chamber.

15 A further feature of the invention is the provision of means for introducing air into the fuel mixture at such time as the motor is running at low speed or is idling.

20 A further feature of the invention is the provision of means for breaking up any globules that may be formed in the fuel prior to discharging the same into the venturi of the carburetor.

25 A further feature of the invention is the provision of means for collecting any globules that may be formed in passing the air through the fuel surrounding the accelerating chamber, and preventing said globules from being discharged with the air through

30 the venturi.

A further feature of the invention is in terminating the tube entering the venturi in line with ports, arranged transversely through the walls of the venturi in the restricted portion of the throat thereof.

35 A further feature of the invention is the provision of a two-point suspension for the float, together with yielding means for regulating the fuel feed opening from the bowl of the carburetor to the air chamber.

40 A further feature of the invention is the provision of an air valve so constructed as to have substantially a dash pot action.

45 Other objects and advantages will be hereinafter more fully set forth and pointed out in the accompanying specification.

Referring to the drawings,

Figure 1 is a vertical central sectional view through the carburetor,

50 Figure 2 is a horizontal section on line 2—2, Fig. 1,

Figure 3 is a view similar to Figure 2 as seen on line 3—3, Fig. 1,

Figure 4 is an enlarged detail sectional view showing the manner of regulating the admission of air while the engine is idling,

55 Figure 5 is an end elevation thereof,

Figure 6 is an edge elevation thereof, and

Figure 7 is a detail top plan view of an agitating means for the float.

60 Referring to the drawings, 1 indicates the bowl of the carburetor and 2 indicates the dome therefor, the upper edge of the bowl 1 having a flange 3 into which the free edge of the dome extends, a shoulder 4 being provided in the interior of the bowl 1 against which the end of the dome rests when the two parts are properly connected together. Extending through one wall of the bowl 1 is an air passage 5 which terminates at its 70 outer end in a right angular extension 6, and through which heated air is conveyed into the interior of the carburetor.

75 The air passage 5 is provided with a discharge end 7, while depending from the crown portion of the dome 2 is an aligned element 8, both of which are interiorly threaded to receive the threaded ends of a connecting tube 9, said tube serving to lock the dome onto the bowl portion of the carburetor.

80 Extending vertically through the bowl 1 and through the air passage 5, is a nozzle 10, the upper end of which extends into a tube 11 arranged axially of the connecting tube 9, the upper end of the nozzle 10 having a discharge opening 12 with which co-operates a needle valve 13 for controlling the discharge of the fuel through the nozzle, the needle valve 13 extending through the lower 90 end wall of the bowl 1 so that it may be regulated from the exterior of the carburetor. In the upper portion of the connecting tube 9 is a venturi 14 which has horizontally extending ports 15 which are preferably located in the most restricted or throat portion of the venturi, and substantially in alignment with the upper end of the tube 11, the ports 15 also extending through the wall 95 of the tube 9, so that the vapor may enter from the bowl of the carburetor and be commingled with the air and fuel discharging into the venturi from the air passage 5 and tube 11.

100 The tube 11 is provided primarily for supplying the fuel when the engine is running

at low speed or idling, under which circumstances the supply of air is not sufficient to properly reduce the richness of the mixture, a secondary passage 16 being provided in the carburetor with which the lower end of the tube 11 connects, and communicating with said passage is an air control 17 comprising a cup-shaped body 18, the closed end of which has a threaded extension 19 thereon for securing the air control to the wall 16' of the secondary passage 16, the body portion 18 being outside of the carburetor while the inner end of the extension 19 communicates with the interior of the passage 16. This air control 17 may be connected to the air passage 16 in any desired manner but preferably with the threaded extension 19 threaded through the side wall of the passage to form communication therewith. Rotatably mounted within the body 18 is a valve 20 through which is formed a port 21 for co-operation with a port 22 extending longitudinally through the threaded extension 19, the ports 21 and 22 being formed at an angle to the axis of the valve 20 and extension 19, so that when the valve 20 is rotated the port 21 will move into or out of registration with the end of the port 22, so that the amount of air passing through said ports may be readily increased or decreased, or entirely cut off, as may be desired. The valve 20 may be retained within the cup-shaped body 18 in any suitable manner as by introducing pins 23 through the outer edges of the body 18, the inner ends of the pins extending into a groove 24 in the peripheral face of the valve, and the outer face of the valve may be provided with a slot 24' into which a tool may be inserted for rotating the valve.

To more thoroughly commingle the air and fuel passing through the tube 11, and also to thoroughly break up any bubbles or globules that might be formed therein, a thimble 25', preferably of wire gauze, is placed over the discharge end of the tube 11, the section of the gauze being such as to thoroughly atomize the particles passing therethrough. The fuel, preferably gasoline, is conveyed from any suitable source of supply through a pipe 25, the end of the pipe 25 being threaded into a tap 26, which is in turn threaded through the wall of the bowl 1, the tap having a port 27 therethrough for the passage of the gasoline.

The flow of the gasoline through the port 27 is controlled by a float valve 28, the stem 29 of which passes through an extension 30 of a float yoke 31, and immediately above the extension 30 is provided with a ball 32 so that the valve may have slight pendulum or swinging action for causing the valve to more uniformly seat. The yoke 31 is preferably constructed of sheet metal and has tongues 33 struck therefrom, which tongues

are so bent as to form bearings for engagement with a pivot rod 34, the ends of said rod being mounted in parts of the walls of the carburetor, consequently the yoke will be given a two-point suspension, so that the float 35 connected with the bifurcated ends of the yoke will positively rest in a horizontal position at all times.

To prevent agitation of the valve 28, due to any bobbing action of the float 35, one end of a spring arm 36 is attached to one section of the yoke 31, and preferably on the opposite side of the pivot rod 34 from the valve stem 29, the opposite end of the arm 36 having a slot 37 through which that portion of the stem 29 above the ball 32 passes, so that the free end of the spring arm 36 will rest upon and normally direct pressure against the ball 32, the tension of the spring arm 36 being such as to prevent undue or uneven agitation of the valve 28, consequently any unusual vibratory or bobbing movement of the float will not affect the operation of the float valve.

The float 35 is normally raised and lowered by the action of the gasoline within the bowl of the carburetor. When the engine creates an undue amount of vacuum in the upper portion of the carburetor, as when the engine is first started, the suction through the pipe line 25 is so great that an over supply of gasoline will be drawn into the carburetor before the float acts to control the admission of the gasoline and causes a fluctuating action of the carburetor. To overcome this objectionable feature an agitating pipe 38 is entered through the bottom portion of the bowl 1, and is connected with the right angular extension 6 of the air passage 5 through a by-pass 39, the upper end of the pipe 38 terminating below the float 35 and preferably at the transverse center of the float, and if desired a hollow head 40 is connected with the upper end of the pipe 38 and curved co-incident to the curvature of the float so as to distribute the pressure of the air from the pipe 38 over a considerable surface of the float 35, the upper face of the head 40 having a plurality of perforations 41 for the escape of the air from the head.

By providing this form of device the sudden increased speed of the motor will not affect the uniform flow of the gasoline into the carburetor, as the pressure of the air which is directed through the by-pass and pipe connected therewith incident to the opening of the throttle to increase the speed of the engine, will automatically raise the float and partially or fully close the float valve 28.

To prevent the gasoline from flowing through the agitating pipe 38 into the by-pass 39, which if permitted to flow might be ignited by a backfire, a ball valve or check

42 is placed in the pipe 38 adjacent the lower end thereof, the interior of the pipe 38 being provided with a seat 43, and when the ball 42 rests thereon completely closes the downward passage through the pipe 38. The ball 42 is limited in its upward movement by introducing a pin 44 through the walls of the pipe 38 and across the opening therein.

The movement of air through the air 10 passage 5 is controlled by a valve 45 which co-operates with a seat 46 formed at the juncture of the right angular extension 6 with the main portion of the air passage 5, said valve having a stem 47 which enters a 15 bore 48 in an adjusting bolt 49 which threads through a cap 50 which in turn threads into an opening in the wall of the air passage 5. The valve 45 is normally held in closed position by means of a spring 51 which surrounds the stem 47 and has one end thereof 20 pressing against the under face of the valve, while the opposite end engages a shoulder 52 on the upper end of the projecting bolt 49, and by adjusting the bolt 49 lengthwise 25 the tension of the spring 51 may be readily regulated.

The introduction of the stem 47 into the bore 48 provides substantially a dash-pot 30 construction for regulating the downward movement of the valve and causing the same to move gradually away from its seat when vacuum is created in the dome of the carburetor, and if preferred a ball valve 53 may be positioned in the lower end of the bore 48 for closing the passage 54 through 35 the head end of the bolt 49. By providing the ball valve 53 air will readily enter the bore 48 on the upward movement of the valve 45, but will be held against rapid escape from the bore on the descent of the 40 valve, consequently causing the air within the bore to cushion the movement of the valve.

The air discharged from the pipe 38, in 45 addition to elevating the float 35, when the vacuum is increased above the float, also serves in a degree to aerate the gasoline and when leaving the gasoline, tends to form bubbles which, if carried into the ports 15, 50 would retard the proper action of the venturi. In order to eliminate such bubbles as may be formed, a baffle plate 55 is placed in the dome 2 at a point above the float and at a point below the ports 15, the outer edge of 55 the baffle plate fitting the interior of the dome while the axial center thereof is provided with an opening 56 for the passage of the tube 9, the opening 56 being preferably formed oblong to provide a passage 57 60 through which the air may escape from the fuel chamber. The baffle plate 55 may be constructed of solid metal or may be formed of mesh wire, and in either instance the passage-way 57 is located at the opposite side

of the vertical axis of the carburetor from 65 the pipe 38, consequently when the air leaves the fuel it will strike the baffle plate and be broken up before it escapes through the passage 57, consequently any drops of fuel carried up by the air will adhere to the under 70 surface of the baffle plate and will eventually descend by gravity into the fuel chamber, thus discharging only the purified air and vapor into the chamber above the baffle plate.

Having thus fully described my said invention, what I claim as new and desire to secure by Letters Patent, is:

1. In a carburetor construction, a bowl portion having a fuel chamber, a detachable dome co-operating therewith, means for connecting the dome with the bowl, a venturi associated with the dome portion of the carburetor having ports through the wall thereof, a tube supported by the bowl having one of its ends entered in said venturi and terminating substantially in line with the horizontal axes of said ports, and an atomizing 80 thimble introduced over the end of the tube entering the venturi.

2. In a carburetor construction, a bowl portion forming a fuel chamber, a dome above said bowl, means for locking the bowl and dome together, said means providing a main air passage through the fuel chamber, a float pivotally mounted in the fuel chamber, 90 a valve controlled by said float, a pipe for conveying air into the lower portion of the fuel chamber and discharging the same beneath and against the free end of said float, and a baffle plate having a passage 95 therethrough at the opposite side of the main air passage from said pipe, the passage in said plate being positioned for causing the air to travel over the under face of the baffle plate for removing excess vapor before entering said passage.

3. A carburetor comprising a bowl portion, a dome associated therewith, a tube for connecting said bowl with said dome the lower end of said tube connecting with an 110 air passage, a venturi in said tube adjacent the upper end thereof having ports therethrough, a second tube axially of the first tube and terminating in the throat portion of the venturi, a fuel nozzle extending into the opposite end of said second tube, means for controlling the passage of fuel through the nozzle, a float in said bowl, means for conveying air into said bowl and against 115 said float, means for controlling the passage of air into said air passage communicating with the first tube, and means for regulating the admission of air into the second tube.

In witness whereof, I have hereunto set my hand at Indianapolis, Indiana, this 12th day 120 of August, A. D. nineteen hundred and twenty-one.

ALBERT E. WEAVER.
